UNITED STATES PATENT OFFICE.

JAMES EDWARD BOND, OF SAWTELLE, CALIFORNIA.

BURGLAR ALARM.

Application filed June 28, 1921. Serial No. 430,986.

To all whom it may concern:

Be it known that I, JAMES EDWARD BOND, a citizen of the United States, residing at Sawtelle, in the county of Los Angeles and 5 State of California, have invented a new and useful Burglar Alarm, of which the following is a specification.

This invention relates to burglar alarms adapted to be attached to a door-way or window-frame and to be operated to sound an 10 alarm whenever the door or window is opened a short distance.

An object of this invention is to construct a simple alarm of this character which will 15 be safe, convenient to attach and set, and certain of operation when the window or door is opened.

Another object is to safely use cartridges for sounding the alarm.

20 Other objects, advantages and features of invention may appear from the accompanying drawing, the subjoined detail description and the appended claims.

The accompanying drawing illustrates the 25 invention.

Figure 1 is an enlarged side elevation partly in section showing the invention in position on the frame of an opening which may be that of a door or of a window. Fragments of said frame are shown and a fragment of a door is shown in closed position and dash lines indicate the position of said door just before the alarm is given. Broken lines indicates the firing position of the 35 hammer.

Fig. 2 is a sectional elevation on line x^2 , Fig. 1, looking in the direction of the arrow.

Fig. 3 is a side elevation of the alarm 40 closed.

The base 1 is adapted to fit upon a frame 2 for the opening 3 that is to be closed by the closure 4. In the drawings the frame, opening and closure are illustrated as pertaining to a door. Said base 1 is provided with a hole 5 through which a screw 6 is extended to fasten the base 1 to the frame 2. Said base is provided with a chamber 7 terminating in a threaded seat 8 and communicating with the outside of the base through a 45 port 9. A cartridge holder 10 is externally threaded as at 11 at one end and has an internally threaded socket 12 and said socket is extended in a smooth bore 13 which communicates with the cartridge chamber 7 and is adapted to receive a cartridge 14 which

may be of any desired type; being shown as a blank rim-fire cartridge. A breech block 15 is screwed into the threaded socket 12 and is provided with the firing pin 16. 60

The hammer 17 is pivoted by pin 18 to a post 19 which in the form shown is bifurcated. Said hammer is provided with a face 20 adapted to strike the firing pin 16 when the hammer is driven down forcibly 65 toward the breech block.

A spring 21 is arranged to operate the hammer 17 on its pivot 18. Said spring is given an appropriate tension and is arranged to apply such tension to the hammer by 70 means of the operating rod 22 which telescopes in a tube member 23 that is loosely seated in the socket 24 and is provided with a shoulder 25 to seat the spring 21, which in turn operates upon the shoulder 25 on 75 said rod 22, that is pivoted by the pin 26 to the heel of the hammer at a distance from the hammer pivot 18. The shoulder 25 on the end of the rod 22 serves as a stop for the hammer when the pivot 26 is stationed 80 toward the pin 16, and beyond a line drawn from the hammer pivot 18 to the pivotal seat 24 of the tube 23. By the arrangement thus shown, the hammer may be easily cocked into the position shown in Fig. 1, and because of the disalignment of the pivot pin 85 26 relative to the pivot 18 and the socket 24, the rod, spring and telescoping tube 23, a portion of the surface of the hammer on the side opposite the breech block 15 is extended 90 beyond the base oblique to the path of the object which is to set off the alarm.

In the case of the door 4 as shown, the opening of the same will force the hammer 17 toward the breech block until the pivot 26 95 is drawn backward beyond the plane passing through the axis of the pivot 18 and the socket 24 and thereupon the force of the spring 21 is actuated to force the telescoping pin up and to drive the hammer face 20 100 down forcibly onto the firing pin 16.

In practice the base will be set with its rear margin 27 at the margin of the opening 3 of the frame member against which the free edge of the closure 4 comes to rest when 105 closed.

In case the closure is moved from its closed position as indicated by the dotted lines in Fig. 1, it will operate upon the oblique surface of the hammer 17 and bring the spring and telescoping pin into position 110 to actuate the hammer and discharge the car-

tridge. A chamber 7 in the base is provided with an orifice 9 to which the force of any explosion in the chamber 9 will be extended and directed.

5 It is understood that this orifice may be variously located; in the form shown it is in the under side of the base as applied to the door frame so that when the cartridge is shot off the force of the explosion will be 10 directed downward by said orifice.

To re-set the alarm all that is necessary is simply to unscrew the breech block from the base and from the cartridge holder then the cartridge may be pushed out by a suitable 15 instrument and a new cartridge inserted.

I claim.

1. A burglar alarm comprising a base having a cartridge holder; a firing pin arranged to discharge a cartridge in said holder; a post secured to said base; a hammer pivotally connected to said post and arranged to engage said firing pin; and a spring arranged to operate the hammer.

25 2. The combination with a base and chamber and a cartridge holder adapted to hold the cartridge in position to fire into said chamber; a firing pin to discharge said cartridge; a pivotally mounted hammer connected to the base; an oscillating spring connected to the hammer and adapted to cause the same to strike the firing pin; and means whereby said spring is oscillatable from and to a position in which it holds the hammer 30 cocked, and to and from a position in which it will drive the hammer to strike the firing pin.

3. A burglar alarm provided with a spring operated hammer pivoted to a support and having a bend adapted to stand in the path of a door or window and means to yieldingly hold said bend in such path and to release said hammer when such bend is pushed out of said path substantially as and 45 for the purpose set forth.

4. In a burglar alarm provided with a cartridge holder and a firing pin and a support for a hammer; a hammer pivoted to said support; a telescoping operating rod 50 pivoted to the hammer and a spring operating in the direction of said rod to operate the hammer, the pivot between the rod and the hammer being arranged to pass dead center relative to the pivot of the hammer 55 when the hammer is cocked, and said hammer being adapted to be moved by the opening of door or window to carry the rod pivot beyond said dead center so that the spring may then operate the hammer to 60 actuate the firing pin.

5. In a burglar alarm the combination with a support and a hammer pivoted to said support, of a spring acting upon the hammer at a point adapted to pass dead 65 center relative to the pivot of the hammer

as the hammer is cocked and uncocked, said hammer having a bend adapted to be acted upon by an opening door or window to move said point past said dead center so that in one position the spring will hold the hammer 70 cocked and when the hammer is moved from cocked position to bring such point past dead center the spring will actuate the hammer.

6. A burglar alarm comprising a base adapted to be attached to a door or window frame, said base having a cartridge chamber therein; a cartridge holder having a bore in communication with the cartridge chamber and adapted to receive a cartridge; a breech block in threaded engagement with 75 said cartridge holder and having a firing pin for discharging a cartridge in the chamber of said base, a post, a hammer pivotally connected to said post for striking said firing pin, and means operated by a door or window for actuating said hammer.

80 7. A burglar alarm comprising a base adapted to be attached to a door or window frame and having a cartridge chamber therein, a firing pin for discharging a cartridge in said chamber; a spring; a bifurcated post secured to said base; a hammer pivotally mounted in said post, said hammer adapted to be held in striking position by said spring, and means whereby opening of a 85 door or window will cause said spring to actuate said hammer to strike said pin.

8. A burglar alarm comprising a base adapted to be attached to a door or window frame, said base having a cartridge chamber therein, a firing pin for discharging a cartridge in said chamber, a bifurcated post secured to said base, a hammer pivoted to said post and having a shoulder; a rod pivoted to said shoulder, a tube telescoping said 90 rod and pivotally connected to said post; a spring under tension arranged between the pivoted end of said rod and the base of said tube; said spring adapted to hold said hammer in striking position; and means whereby opening of a door or window will cause said spring to actuate said hammer against said pin.

9. A burglar alarm comprising a base adapted to be attached to a door or window frame said base having a cartridge chamber therein, a firing pin for discharging a cartridge in said chamber; a bifurcated post secured to said base; a hammer pivoted to said post and provided with a shoulder; a rod pivotally connected to said shoulder; a tube telescoping said rod and movably seated in a socket between the limbs of said post; a spring under tension arranged between the pivoted end of said rod and the seat of said tube, said spring being adapted to hold said hammer in striking position with said shoulder abutting a stop on said post and the pivot pin of said rod and shoulder off center to a line through the 100 105 110 115 120 125 130

pin pivotally connecting said hammer and post and the center point in the seat of said cylinder; means whereby opening of a door or window will engage said hammer to move 5 the center of the pin pivotally connecting said rod and shoulder across the line between the centers of the pin pivotally connecting the hammer to said post and seat of said cylinder so that tension of said

spring will strike said hammer against said 10 firing pin for the purpose specified.

In testimony whereof, I have hereunto set my hand at Los Angeles, California, this 17th day of June, 1921.

JAMES EDWARD BOND.

Witness:

JAMES R. TOWNSEND.
